CLAIM

The ornamental design for a tire, as shown and described.

DESCRIPTION

The patent or application file contains at least one drawing executed in color. Copies of this patent or patent application publication with color drawing(s) will be provided by the Office upon request and payment of the necessary fee.

1. Tire

1.1 : Front

1.2 : Right

1.3 : Perspective

1.4 : Enlarged

1.5 : Enlarged

It is understood that the claimed tire tread pattern is intended to be applied to the entire surface of the tire, and repeat uniformly across its entire surface. The red box with the indication "A" disclosed in reproduction 1.1 identifies an enlarged view of the tire as shown in reproduction 1.4. The red box with the indication "B" disclosed in reproduction 1.3 identifies an enlarged view of the tire as shown in reproduction 1.5.
